UNITED STATES PATENT OFFICE.

WILLIAM J. HUGHES, OF BALTIMORE, MARYLAND.

LIQUID MEASURE AND REGISTER.

1,114,989.

Specification of Letters Patent.

Patented Oct. 27, 1914.

Application filed September 24, 1910. Serial No. 583,640.

To all whom it may concern:

Be it known that I, WILLIAM J. HUGHES, a citizen of the United States, residing at Baltimore city, State of Maryland, have invented certain new and useful Improvements in Liquid Measures and Registers, of which the following is a specification.

This invention relates to improvements in oil wagons, and has particular reference to 10 attachments therefor to measure and register the fluid drawn therefrom.

One object of the invention is to provide a measuring receptacle into which the fluid contained in the tank on the wagon is drawn, 15 and the number of times the said receptacle is filled, is checked by a suitable registering mechanism.

Another object is the provision of an inlet 20 and outlet valve, operable by a lever mechanism so that when one valve is opened the other is closed, in order to permit the measuring receptacle to fill and empty according to the movement of the lever.

A further object is to provide means in 25 connection with the inlet valve to permit the entrance of air to the receptacle, to assist in the outward flow of the fluid therein drawn, and when the outlet valve is open.

A still further object is to so construct the 30 registering mechanism that when the limit of its register has been reached, any further attempt at the device, to draw more fluid, would result in the destruction of one of the counter wheels, thus indicating that an attempt had been made to defraud the employer.

Other objects and advantages will appear as the description proceeds.

In the accompanying drawing, in which 40 is shown a device of the character described, made in accordance with my invention, Figure 1 is a side elevation of a tank wagon, showing my invention applied thereto, Fig. 2 is an end view of the same, Fig. 3 is a vertical longitudinal sectional view through the measuring receptacle, the valves being in position to permit the filling of the receptacle, Fig. 4 is a similar sectional view showing the valves in position to empty the receptacle, 45 Fig. 5 is a front elevation of the measuring receptacle, the cover of the counter or registering mechanism being removed, Fig. 6 is a rear elevation of the same, showing the

position of the locking pawl for the hundredths wheel, Fig. 7 is a vertical section on 55 the line 7—7 of Fig. 5, Fig. 8 is a section on the line 8—8, of Fig. 5. Fig. 9 is a section on the line 9—9 of Fig. 5, looking in the direction of the arrows, Fig. 10 is a perspective view of the inlet valve, removed from its 60 seat.

Referring now to the accompanying drawings, A represents a wagon having suitably mounted thereon a tank B, both of which are of the common type used in the oil 65 trade, for dispensing oil, the latter of which is provided with a threaded nipple 1, by means of which my invention is readily applied to the tank.

A receptacle 3, having the vertical parallel 70 side walls 4, and the front and rear parallel walls 5 and 6, is provided in the said rear wall 6 with an interiorly threaded nipple 2, adapted for attachment to the nipple 1 of the tank B. The said nipple 2 projects 75 rearwardly from the upper portion of the rear wall 6 of the receptacle, and in said nipple adjacent the receptacle is formed the valve seat 8, extending transversely of the receptacle, and in which is seated the plug 80 valve 9. This valve is a straight way valve having the transverse passage 10 there-through, and the smaller passage 11 passing through one of the side walls of the passage 10, and letting into the receptacle, when the 85 valve is in the position of Fig. 4. In the top of the casing of the receptacle 3, and letting into the valve seat 8, is an air inlet 12, which, when the valve 9 is in the position shown in Fig. 4, will permit air to pass through the 90 passages 10 and 11, and into the receptacle. This provides for the admission of air to assist the fluid in the receptacle to pass out through the spout 13, located at the forward end of the receptacle. 95

The receptacle 3 has its upper and lower walls 14 and 15 inclined downwardly toward the front wall 5, so that the liquid within the receptacle would more readily flow toward the front wall and through the 100 spout 13. In the lower forward portion of the receptacle, and communicating with the spout 12, is a valve seat 16 for the reception of the oscillatory valve 17 similar to the valve 9, this valve having a passage 17', 105 which will be more fully referred to here-

inafter. The stem of the valve 9 has an arm 19 secured thereto, while the stem of the valve 17 has an arm 18 secured thereto, these arms being pivotally connected together by 5 means of the link 20, to provide for their simultaneous movement by a single movement of the arm 18. The arm 18 extends vertically above the pivotal point of the link 20, to provide a handle by means of which 10 the valves are oscillated. When the lever 18 is drawn forwardly, the valves 9 and 17 will be turned into the positions shown in Fig. 4, the valve 9 being closed to cut off communication from the tank B and the 15 valve 17 open to permit the liquid in the receptacle 3 to pass through the spout 13. The normal positions of the valves and levers are shown in Figs. 1 and 3, where the valve 9 is open to permit fluid from the 20 tank B to pass into the receptacle 3. Mounted in the front wall of the receptacle 3, above the spout 13 is a pop valve 21 to which is connected a curved pipe 21' extending into the receptacle 3 and terminating at a point adjacent the valve 9. In the 25 forward wall 5 and establishing communication between the pop valve and the valve seat 16 is a short diagonal passage 5'. When the receptacle 3 is full, the air in the upper 30 portion of the receptacle will pass out through the pipe 21' and through the pop valve 21. The air will issue with a slight hiss so that the fact that the receptacle is full will be clearly indicated. When the 35 handle 18 is thrown to close the valve 9 and open the valve 17, the passage 17' in the valve 17 registers with the passage 5' so that the oil in the pipe 21' which splashes thereto during the filling of the receptacle 3 40 will flow through the passage 5', passage 17', and be drawn out by the oil issuing from the receptacle through the spout 13. The opening 11 in the valve 9, and the opening 17' in the valve 17 are so positioned with 45 respect to each other that when the transverse passage in the valve 17 is in registry with the passage 5' the opening 11 will be in communication with the interior of the receptacle, and at the same time the passage 10 will be in communication with the opening 12. This permits air from without 50 the receptacle to enter the receptacle during the emptying of the receptacle.

The receptacle illustrated in the accompanying drawings is intended to contain five (5) gallons, but receptacles containing more or less may be used as conditions require.

On the end of the valve 17 opposite to that which carries the lever 18, and exteriorly of the receptacle 3 is mounted a registering mechanism. This end of the valve has formed integral therewith a reduced cylindrical extension 22, and secured

thereon is a disk 23. Pivotedly carried on this disk is a pawl 24 which engages with a ratchet wheel 25 formed integrally with a combination units-and-tens counterwheel 26 loosely mounted on the extension 22. On the outer side of the counterwheel 26, and formed integrally therewith is a disk 27 carrying a single radial tooth 28 which is arranged for engagement with a pinion 29 mounted on a shaft above and parallel with the extension 22. Beyond the disk 27, and loosely mounted on the extension or shaft 22 is a hundreds counterwheel 31, this wheel carrying an integral gear 32 which constantly meshes with the pinion 29. It will thus be seen that when the valve 17 is rotated, the disk 23 will move the pawl into engagement with the ratchet wheel 25 and cause a partial rotation thereof together with the counterwheel 26. The counterwheel 26 is provided with numbers on its peripheral face in multiples of five (5) up to ninety-five (95) while the counterwheel 31 has the numbers in multiples of one (1) up to nineteen (19), thus making the full capacity of the register 1995, but this may be varied according to conditions as required.

Secured to the side of the receptacle 3 and embracing the countermechanism is a support which includes the upper and lower outwardly extending parallel portions 34 and 34' which are connected by a vertical portion 33. The outer end of the extension or shaft 22 is journaled in this vertical portion 33. This support is secured by means of the bolts 35. The registering mechanism 100 is suitably housed, and this housing is provided with a hinged cover 42 in which is formed a sight opening (not shown). In the lower portion 34' is formed a slot 36, and depending in this slot is the weighted 105 enlargement 24' of the pawl 24. This weight is adapted to engage the end wall of the slot when the disk 23 is rotated by the valve 17, and lifts the weighted end of the pawl so as to release the nose thereof from 110 engagement with the ratchet wheel 25. The nose of the pawl 24 is in engagement with the tooth of the ratchet wheel 25 when the weighted end 24' depends through the slot, and when the disk 23 is given a partial rotation, the pawl will move the ratchet wheel the distance of one notch and then be rocked away from the ratchet wheel when the weight 24' engages the end wall of the slot 36. By this arrangement the 115 counterwheel 26 is turned one notch at the same instant that the valve 9 begins to close and the valve 17 to open, thus preventing the drawing of the contents of the receptacle 3 without first registering the amount 120 contained therein.

With the device as thus far described, it would be possible for the salesman to work the lever 18 back and forth, and draw out an amount of fluid, say about two (2) gallons, after he had completed his day's sales, and pocket the receipts of the two (2) gallons. Suppose the amount of the day's sales to be five hundred (500) gallons. The register would indicate that five hundred (500) gallons had been sold, and by working the lever 18 back and forth, oil or other fluid could be drawn from the receptacle 3 while at the same time the register would be turned to the limit of the register, 5 and back to the five hundred (500) mark again. Thus five hundred and two (502) gallons would be drawn; and the amount drawn which exceeded the five hundred gallons, would be lost to the employer, and evidence of the loss be lacking unless the tank B were emptied and its contents measured. To obviate this fraudulent process, I provide the hundreds wheel with an annular groove 37 in one of its side faces, in which 10 is adapted to ride the nose 40 of a spring pressed pawl 39. At a point 38, in the annular groove is formed a stop notch, into which the nose of the pawl is adapted to drop, to prevent the further movement 15 of the register. This pawl is pivotally mounted on a support 41, on the bottom wall 34 of the support for the registering mechanism, and has its lower end projecting at right angles to the body of the pawl and 20 in a plane parallel with its pivot, said projecting end forming a finger piece 40', by means of which the pawl is released from the notch 38, when the register is to be reset. This notch is so placed with relation to the 25 number on the disk 31 corresponding to the capacity of the tank B, that any attempt to manipulate the counter would be frustrated by the fact that the pawl 39 locks said disk from any further rotation, without 30 injury to the counterwheel 31. Thus when the arm 18 is manipulated for the last time, to draw the last five gallons from the tank B, the pawl 40 will enter the notch 38, at the same time that the highest 35 number of the register appeared through the sight opening. Were the counterwheels made of metal, it would be possible, by using force, to bend the pawl out of the way, and permit the wheels to rotate beyond the limit 40 of register, and farther to the number desired to be shown through the sight opening in the cover 42, to indicate the total of gallons sold, and for which returns were to be made to the employer. At the same 45 time fluid could be drawn from the tank, and not be detected. To avoid this I make the counterwheel 31 of hard rubber, or other suitable frangible substance, and very thin,

so that it will break when the nose of the pawl 39 enters the notch 38, and an attempt 50 is made to actuate the register beyond the limit of registration thereof. Thus the employer would know by the broken wheel when he had opened the cover of the register, that an attempt had been made to 55 defraud him. The finger piece of the pawl is located within convenient reach when it is desired to set back the register. The cover of the registering mechanism is provided with a suitable lock 43, to prevent 60 access to the mechanism, except by authorized parties.

The valves, the lever mechanism, and the counter or register are so correlated that the number of gallons are registered the 65 instant the valves begin to change their positions, or to be more accurate, the register operates slightly prior to the opening of the inlet valve, so that the amount to be drawn is registered and of necessity has 70 to be drawn.

From the foregoing, it will readily be seen that I have provided a simple and efficient device of this character, which will put a check on the sales made by the employees, and positively indicate when any fraudulent act has been tried on the device, thus revealing any dishonesty on the part of the employees. The fact that the inlet valve is so timed with relation to 75 the register makes it impossible for the dishonest salesman to draw less than the capacity of the receptacle 3, without registering the full capacity of said receptacle. Should the salesman desire to sell an amount 80 of oil less than five (5) gallons so that he could pocket the money, he would have to register five (5) gallons in order to draw less than that amount.

What is claimed is:

105

1. A pawl and ratchet device for a registering mechanism including a supporting frame, a rock shaft mounted in the frame, a disk fixed on the shaft, a ratchet wheel loosely mounted on the shaft adjacent the 110 disk, a spring pressed pawl pivotally carried by the disk and engaging the ratchet wheel, said pawl having a weighted end, and means on the frame for engagement by the said weighted end to rock the pawl out of engagement with the ratchet wheel after the pawl has moved the ratchet wheel the required distance.

2. A registering mechanism including a support, a shaft, a disk fixed on the shaft, 120 a spring pressed pawl pivotally carried on the disk, said pawl having a depending weighted enlargement, the lower portion of the support being slotted to receive the depending weighted portion, said depending 125 portion being adapted to engage the end

wall of the slotted portion, during a part of the movement of said disk, a ratchet wheel loosely carried by the shaft and engaged by said pawl, said pawl being released from contacting with said ratchet wheel when the weighted enlargement engages with the end wall of the slot.

In testimony whereof I affix my signature, in the presence of two witnesses.

WILLIAM J. HUGHES.
